(57) **CLAIM**

The ornamental design for baroque arms for eyeglasses, as shown and described.

DESCRIPTION

FIG. 1 is a front, left-side and top perspective view of the left arm of the baroque arms for eyeglasses, showing the new design;

FIG. 2 is a front elevational view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof, and the right arm of the baroque arms for eyeglasses is symmetrical with the left arm, such that the right and left side views of the right arm are mirror images of the left and right side views of the left arm, respectively, and the top, bottom, front and back views of the right arm are mirror images of the top, bottom, front and back views of the left arm, respectively.
